DESIGN FOR A CLIP OR SIMILAR ARTICLE

Joseph Wuyts, New York, N. Y., assignor to Mazer
Brothers, New York, N. Y., a copartnership

Application October 16, 1940, Serial No. 95,873

Term of patent 3½ years

To all whom it may concern:

Be it known that I, Joseph Wuyts, a citizen of the United States and a resident of New York city, in the county of New York and State of New York, have invented a new, original, and ornamental Design for a Clip or Similar Article, of which the following is a specification, reference being had to the accompanying drawing, forming part thereof, and in which—

Fig. 1 is a side view of the clip showing my new design,

Fig. 2 is a top view thereof, and

Fig. 3 is a rear end view thereof.

I claim:

The ornamental design for a clip or similar article, substantially as shown.

J. WUYTS.
